UNITED STATES PATENT OFFICE.

BURNHAM C. STICKNEY, OF ELIZABETH, NEW JERSEY, ASSIGNOR TO JACOB FELBEL, OF NEW YORK, N. Y.

TYPE-WRITING MACHINE.

SPECIFICATION forming part of Letters Patent No. 658,981, dated October 2, 1900.

Application filed April 4, 1900. Serial No. 11,461. (No model.)

To all whom it may concern:

Be it known that I, BURNHAM C. STICKNEY, a citizen of the United States, and a resident of Elizabeth, in the county of Union and State 5 of New Jersey, have invented certain new and useful Improvements in Type-Writing Machines, of which the following is a specification.

The present invention relates to type-writing machines; and its object is to produce a machine in which writing may be done upon either wide or narrow sheets, as desired, and in which all of the written portion of the page shall be constantly in full view of the operator. 10 Heretofore paper-guides adjustable along the platen have been employed for the purpose of guiding wide or narrow sheets; but such guides have been mounted upon a rod or bar which intercepts the view of some of the writing portions of the page. In carrying out my invention I arrange paper-guides adjustably upon a bar which does not come between the written lines and the eyes of the operator. I prefer to mount the bar over the platen and 15 at a point where the paper may pass over the same as it emerges from the machine and to mount upon said bar arms which may be adjusted therewith and which carry at their forward ends paper-guiding devices, the latter being arranged inwardly or laterally of 20 said arms. Thus the arms are arranged out of the path and at either side of the paper, the edges or margins of which are gripped or pressed by the said guiding devices. Means 25 are provided for adjusting the pressure of the guiding devices against the platen. In order to facilitate the proper insertion of the paper in the machine, I attach a rearwardly-extending gage-arm to each of said adjustable 30 paper-guide supports.

My invention further consists in certain combinations of devices and features of construction, all as will be hereinafter more fully set forth, and particularly pointed out in the 35 concluding claims.

In the accompanying drawings, in which my invention is shown as adapted to a front-strike type-writing machine invented by Jacob Felbel and in which the ink-ribbon, 40 key-levers, and other common parts are omitted, Figure 1 is a front elevation of the paper-

carriage and part of a type-bar system, a partly-written sheet being shown upon the platen. Fig. 2 is a vertical transverse section taken about midway of Fig. 1. Fig. 3 is a perspective view of a metallic paper guide or finger and the adjustable support to which it is pivoted. Fig. 4 is an enlarged view of a spring-carrying sleeve. Fig. 5 is an enlarged horizontal sectional view, showing one end of a rod along which the paper-guides are adjustable and the method of mounting one end of the rod in the platen-frame. Fig. 6 is a section taken at the line *x* of Fig. 7, but omitting the spring. Fig. 7 is an enlarged plan, partly in section, of the yoke portion of one of the adjustable supporting-arms of the paper-guides and of the spring mechanism connected therewith. Fig. 8 is a plan view of the carriage and embodying my improvements. Fig. 9 is a view showing a modified paper-guide and also showing a pack of sheets as passing around the platen. Fig. 10 is a view showing another modification of paper-guide. Fig. 11 is a view similar to Fig. 3, but showing the manner of mounting a small pressure-roller to work in conjunction with the curved paper-guide. Fig. 12 is a plan view of the carriage, showing the modification illustrated at Fig. 10.

Throughout the views like numerals of reference designate like parts.

1 indicates a platen, whose shaft 2 is journaled in side bars 3 4 of a U-shaped platen-frame, said side bars being rigidly united in 85 rear of the platen by a longitudinal bar 5. The platen-frame may be mounted in any suitable manner to slide upon rails 6 and may be provided with the usual escapement devices. (Not shown.) Concentrically arranged type-bars 7, whose common printing-point is indicated at 8, Fig. 1, lie normally in a horizontal position in front of the platen and swing upwardly about a pivot-rod 9 to make their impressions upon the paper. Any 90 suitable key-controlled devices may be provided for operating the type-bars. A type-guide is indicated in dotted lines at 10, being secured by screws 11 to a top plate 12. Any suitable fixed or swinging type-guide may be 95 used, or, if desired, the type-guide may be omitted and the type-bars controlled by their 100

5 pivots. Extending along the platen, in rear thereof, is a pressure-roller 13, carried by any suitable yielding or springy arms 14, which may be secured to the platen-frame, 10 as by screws 15. Arranged between this roller and the printing-point is a second roller 16, which may be made up of three sections, as shown at Fig. 1, and which is carried by the forward ends of springy extensions 17 of 15 the arms 14. Each of the rollers 13 and 16 serves to press the paper against the platen so as to cause it to feed toward the printing-point. An apron or deflector 18 is fixed upon a rock-shaft 19, which is pivoted at 20 in the 20 side arms of the platen-frame and provided with a spring 21, which latter causes the forward portion of said apron to press normally against the platen. The apron is provided with suitable apertures 22 for the pressure-rollers 13 and 16. Any other suitable paper-feeding devices may be employed in lieu of those illustrated.

25 A platen-scale 23 extends along the platen, contiguous thereto and below the printing-point, and is supported upon obliquely-arranged arms 24, whose lower ends are hinged upon studs 25, extending inwardly from extensions 26 of the end bars of the platen-frame. A spring 25^a, surrounding one of 30 said studs, serves to press the scale-plate 23 lightly against the platen. The plate may be otherwise supported.

35 A pair of yielding or springy paper-guides 27, bent to conform substantially to the curvature of the platen and made, preferably, of sheet metal, are arranged in front of the platen, their lower ends overlapping the scale-plate 23 and their upper ends extending rearwardly and over the platen. As these guides 40 and their supporting devices and spring mechanisms are substantially alike, although oppositely arranged, only one of them will be described in detail. About midway of its length the guide or finger 27 is provided with 45 a lateral extension 28, which is bent up at 29 to form an ear. The guide itself is provided with a second ear 30, in line with the ear 29, and both ears are perforated and pivoted upon a horizontal pin 31, which extends laterally from the forward end of a support or 50 arm 32 and is rigidly secured thereto. This arm 32 is arranged laterally of the guide 27 and out of the path of the paper, the edge of which passes along by the side of said arm 32 55 and not beneath or over the same and is not obstructed thereby. At its rear end the arm 32 is bent inwardly at right angles at 33 and is again bent forwardly at 34 to form an ear. Said ear is perforated at 35 in line with a perforation 36 upon said arm, said perforations being adapted to engage pivotally and slidably a rod, shaft, or bar 37. It will be observed that by means of the yoke-like construction formed by the bending of the metal 60 at 33 and 34 the arm 32 is given a long bearing upon the rod 37 and that said arm may both vibrate and slide freely upon said bar,

while the forward end of said arm is not liable to become skewed. The yoke is preferably arranged upon the same side of the arm 70 32 as the paper-guide, thus economizing room in the machine.

75 The spring mechanism for pressing the paper-guide against the platen, or, in other words, for affording a yielding support for said paper-guide, comprises a sleeve 38, mounted upon said rod and provided with a key 39, which engages a groove 37^a, extending longitudinally of the rod, whereby said sleeve is splined thereto. At one end a collar 39^a, 80 having crown ratchet-teeth 40, is fixed upon said sleeve. A similar crown-ratchet 41 is loosely mounted upon said sleeve and engages one end of a spring 42, which is wound along said sleeve and whose other end bears 85 at 43 in a hole or notch formed in said yoke, the tension of the spring being such as to cause the forward end of the arm 32 to press toward the platen. The loose ratchet-collar 41 may be turned upon the sleeve 38 to increase or decrease the tension of the spring 42, and thereby cause the paper-guide 27 to press with greater or less force upon the platen or the paper thereon, suitable holes being formed in the ratchet to receive a turning-tool and the spring 42 having preferably 90 an endwise expansive tension to cause re-engagement of said ratchets after adjustment. Either of said springs 42 may be adjusted independently, and owing to the confinement of the sleeve 38 within the said yoke 95 33-34 the said sleeve, spring, and ratchets are caused to move simultaneously with the arm 32 and guide 27 when the latter are adjusted along the platen. The arm 32 is preferably provided with an upwardly-extending ear or finger-piece 32^a, which may be grasped 100 when it is desired to adjust the arm upon the rod 37. The cylindrical rod 37 extends parallel with the platen and is arranged over the platen and in rear of the vertical line 105 passing through the platen-axis, and it will be observed that the paper-guide, which extends from the platen-scale partly around the platen and to a point in proximity to said rod 37, is flared or bent upward at its rear end 27^a in order to direct the paper over said rod, as indicated by dotted line at Fig. 2. One end of the rod is loosely or slidably journaled at 44 in the right-hand bar 4 of the 110 platen-frame, and the other end thereof is journaled in a bushing 45, which is screwed into a threaded hole in the left-hand bar 3. The rod 37 extends beyond the bar 3 and at 115 its outer extremity is provided with a cap 46. The bushing 45 is provided with crown ratchet-teeth, which engage the teeth of a crown-ratchet 47, secured to the rod and having an enlarged portion 48, which is knurled to afford a grip for the fingers, so that said 120 rod may be turned for adjustment, the teeth of the ratchet automatically reengaging at any point to which the rod may be turned, a compression-spring 49 being provided 125 be-

tween the cap 46 and the outer side of the bar 3 to cause such engagement. By means of this construction both of the springs 42 may be adjusted simultaneously, owing to 5 their connection with the groove 37 in the rod.

At 50 is indicated a rearwardly-directed extension formed upon the arm or bar 32 and reaching to a point behind or in rear of the front or working face of a paper-shelf 51, 10 which may be secured in any suitable manner upon the platen-frame, as by screws 52. Preferably a depression 51^a is formed longitudinally in the lower portion of said paper-shelf, and the rear end of the extension 50 15 works in said depression, whereby the paper is prevented from accidentally getting behind the end of the extension. The device 50 forms a gage for assisting the operator to place the sheet properly in the machine, so that when 20 the sheet is set around and up over the platen it will not come in contact with the arm 32. The extension 50 is preferably offset or arranged laterally of or out of line with the arm 32, so that a slight clearance may be 25 secured between the edge of the paper and the said arm. It will be observed that as the paper-guiding device is adjusted along the rod the gage 50 is automatically adjusted accordingly and simultaneously, and inasmuch 30 as the paper-guide 27, which extends downward to the platen-scale plate 23, is positively connected to the gage 50 it will be seen that the gage may be adjusted by reference to the platen-scale—that is, by noting the point at 35 which said paper-guide 27 is positioned along said scale. At Fig. 8 the right-hand paper-guide and its support are shown in dotted lines as adjusted toward the left upon the rod 37 to accommodate a narrow sheet of paper, 40 the gage 50 indicating to the operator the point at which the paper may be inserted.

In operation each of the paper-guiding devices is adjusted as desired by manipulation of the finger-piece 32^a, the friction of the 45 paper-guide against the platen and of the spring mechanism upon the rod 37 being sufficient to hold the arm 32 in its adjusted position. The paper is then inserted in the machine behind the rod 37 and enters the opening 50 between the platen and the apron 18, the guards and gages 50 preventing the paper from being inserted out of position—that is, from being placed too far to the right or to the left. The leading end of the paper passes 55 into the bite of the pressure-roller 13 and is thereby fed along toward the printing-point, passing between the platen and the apron or plate 18, the roller 16, and the platen-scale 33, said devices yielding sufficiently to permit 60 the entrance of the paper and the roller 16 assisting in the feeding operation. The paper then enters between the paper-guides 27 and the platen, being engaged by the overlapping lower ends of the guides, and is thereby guided 65 away from the printing-point and upwardly and rearwardly over the platen and passes onward over the bar 37. The lateral arms 32,

which support the guides, have a yielding motion to accommodate different thicknesses of paper, while the guides themselves are sufficiently flexible and elastic to press the paper evenly. The pivotal connection between the guide and the supporting-arm insures that the pressure shall be applied to the paper partly above and partly below the pivotal point, thus 70 increasing the efficiency of the guide. The writing is performed in the usual way, and, as will be noted by reference to Fig. 1, every line written upon the page is constantly in view of the operator, which would not be the 75 case if the paper-guides were made adjustable along a bar arranged in the line of vision, as in prior machines. The operator is thus enabled to refer instantly to any part of the written page, either for the purpose of ascertaining errors or for making comparisons 80 of the work done upon different parts of the page, as is sometimes the practice in tabulating and similar difficult work. The invention also enables a person who is dictating directly to a machine operator to refer to every part of the work during the progress thereof, thus enabling him to freely pursue the thread of the argument or discourse and avoid repetitions and ungrammatically-constructed sentences. As each line is written, the paper is fed forward in any suitable or usual manner until the page is filled, all of the writing remaining constantly in view. So long as this result is attained it is not essential that the paper-guiding fingers be adjustable along a bar which is arranged over the platen, although I prefer this construction. If it now be desired to write upon narrow sheets, either or both of the guides may 90 be adjusted along the bar 37, as required, and the insertion of the paper and writing may proceed as before. When the guide 27 has been adjusted to a position for carrying a narrow sheet, it is necessary for it to pass behind the type-guide 10, if one be used, as otherwise the paper-guide would be liable to collide therewith during the manipulation of the carriage. The type-guide is usually placed close to the platen, and although there is room 95 for the thin paper-guide 27, still it is not desirable to place the type-guide so far from the platen that the arm 32 could pass between them, and hence I construct said arm to pass over said guide, so that there is ample clearance, as will be seen by reference to Fig. 2, 100 in which the arm 32 is shown as terminating at a point above the type-guide 10. After the paper passes beyond the roller 16 the guides 27 suffice to feed it up the short remaining distance. In case the paper becomes skewed, one of the springs 42 may be tightened to increase the tension of the corresponding paper-guide, so as to cause the paper to feed truly. If the pressure upon both guides 105 should be too weak to suitably control a stiff sheet or a pack of sheets, the rod 37 may be given a partial rotation by means of the thumb-piece 48, thus increasing the tension 110

upon both of the springs 42 and causing greater pressure upon part of both paper-guides 37, the ratchet 45 serving to hold the rod in its adjusted position.

5 Referring now to Figs. 10 and 12, it will be seen that the forward end of the arm 32 is bent inwardly and that the paper-guide 27^b is riveted to the inner end of the bent portion instead of being pivotally carried upon 10 the arm. The splined sleeve 38^a is rigidly secured to the arm 32, and a single spring 42^a serves to press both paper-guides against the platen, said spring being wound about the left-hand end of the rod 37^a and secured at 15 one end to said rod and at the other end to the side bar 3 of the carriage. The rearwardly-extending gage 50 passes beneath the lower edge of the paper-shelf 51^a, which is unprovided with a depression. The paper-apron 20 18 at these figures is prolonged, so that its forward end may serve as a straight-edge for adjusting the paper, and it may, if desired, be provided with graduations. It will be noted that the lower end of the paper-guide 25 27^b overlaps the forward end of the apron or plate 18. Although a paper-finger 27^b, rigidly connected to the arm 32, will serve the main purpose of my invention, still I prefer the pivotal connection above described, as a better-distributed pressure upon the paper is secured.

The modification shown at Fig. 9 is similar to that shown at Figs. 10 and 12, except that the paper-guide is looped at its upper end, 35 and the forward end of the arm 32 is rigidly secured at 32^b to the outer termination of the looped portion. The looping of the spring 27^c serves to give the latter a more yielding quality than in the modification shown at 40 Fig. 12, so that the paper is given a more even pressure throughout the length of the working face of the spring. At Fig. 9 a pile of sheets is illustrated as passing through the machine and the arm 32 is illustrated as having vibrated upwardly to accommodate the 45 extra number of sheets.

Referring now to Fig. 11, a small sheet-metal frame 53, consisting of a pair of side arms and a cross-arm, is pivoted by its side arms upon 50 the fixed pin 31, which projects laterally from the arm 32, and between said arms at their upper ends is journaled a small pressure-roller 54, which works in an opening 55, formed in the paper-guide 27 above its pivot. The 55 roller is pressed toward the platen independently of the paper-guide 27 by means of a spring 56, which is coiled about the pin 31 and bears at one end upon the frame 53 and at the other end engages a hole in said pin.

60 It will be noted that the paper-guiding devices 27 may be adjusted along the platen independently of the roller 13, or of the roller 16, or of the plate 18, or of the platen-scale 23. The construction of the devices 27 is 65 preferably such that the paper is positively deflected rearwardly over the point at which it is inserted in the machine. The guiding-

finger 27 extends from the scale-plate 23 upwardly and rearwardly over the platen and to a point in proximity to the bar 37. The 70 pressure-roller 16 is arranged in proximity to the lower end of said guide 27, so that the paper is positively controlled in its travel through the machine. It will also be seen that the arm 32 extends forwardly from the 75 rod 37 toward the printing-point and is provided with a single lateral projection, that the paper-guide 27 is wholly supported upon said projection, and that said paper-guide is 80 preferably movable relatively to said arm.

While I have shown my improvements as applied to a front-strike writing-machine, it is obvious that they may also be adapted either to a top-strike machine or to a machine in which the writing is done upon the upper 85 front side of the platen, which latter I regard as a front-strike machine. Certain features of my improvements may also be applied to under-strike machines—such, for instance, as the gage which is automatically set to position when the paper-fingers are adjusted along the platen. Many minor changes may be made in the construction and arrangement of the parts in applying the invention to various machines without departing from 90 the spirit of my invention, the gist of which resides in providing, for the front paper-guides of a front-strike writing-machine, supporting arms or devices which are arranged at the delivery side of the platen and which are prolonged or extended to points wholly outside of the field or area which lies between the printing-point and the point of issuance of the paper and in mounting said arms or devices at their extended ends upon 95 a bar arranged longitudinally of the platen and so placed that the paper as it feeds away from the printing-point does not pass between the bar and the platen, so that either wide or narrow sheets may be written and 100 so that there shall be no obstruction between the eye of the operator and the written matter occasioned either by the said supporting devices or by said bar or otherwise. By the 105 term "point of issuance of the paper" I 110 mean the point or place where the paper leaves the guide—as, for example, at X, Fig. 2.

One feature of the invention resides in mounting the bar that supports the paper-guiding devices back of or behind the line of 115 passage or pathway of the paper, which is determined by said guiding devices, so that the leading end of the sheet shall be fed onward or rearwardly in front of said bar and so that the view of no portion of the printed matter shall be intercepted thereby; but it will be understood that so far as this feature of the invention is concerned the particular position, location, or arrangement of said bar back of or behind the said pathway of the 120 paper may be quite different from that herein shown—that is to say, while I have shown said bar as immediately behind the path which the paper takes after the printing op-

eration and while I prefer it in the position shown it will nevertheless be seen that the said bar may be carried back or behind or to the rear to any desired extent so long as the supporting-arms are extended in length and of suitable shape, so as to support the guiding devices at the proper or desired portion of the platen. Hence where in the claims I refer to the paper as passing over the bar after the printing operation it is to be understood that these terms are to be construed broadly and as not being limited to the exact or even approximate position of the bar shown in the drawings, which particular arrangement I have preferred to use in carrying out my invention, more particularly on account of the facility thus afforded for the adjustment of the paper-guides.

It will be observed that I have provided, in connection with means for guiding and feeding the paper from its entrance into the machine toward the printing-point, a pair of pressure devices constructed and arranged wholly independently of said guiding and feeding means for receiving the paper from said guiding and feeding means and conducting it away from the printing-point, said conducting devices being each provided with a supporting-arm arranged at the delivery side of the platen and said supporting-arms being so mounted at their extended ends upon a bar arranged longitudinally of the platen that they may be adjusted along said bar without liability of interference from and wholly independently of said devices for guiding and feeding the paper toward the printing-point and said bar being also so arranged that the paper as it is conducted away from the printing-point does not pass between the bar and the platen. By the term "delivery side of the platen" I refer to the portion thereof traversed by the paper after it passes the printing-point or the portion between the printing-point and the point of introduction of the paper. The guiding-fingers are mounted independently of and adjustable along the plate or scale 23, which extends longitudinally of the platen and forms part of the means for feeding the paper toward the printing-point. Said guides are constructed at one end to receive the paper from the devices which guide and feed it toward the printing-point and at the other end to positively deflect the paper rearwardly over the point at which it is inserted in the machine. Said adjustable guiding devices extend forward directly over or upon the upper side of the platen from the bar 37, and the latter is placed forward of the point of entrance of the paper into the machine. The lateral supports 32, which extend from the bar 37 in a direction opposite that of the advance movement of the paper and overhang the platen, form a passage-way for the paper as it issues from the machine, or, in other words, the paper passes out between or by said supports. The purpose of loosely mounting the curved device 27 upon the spring-

pressed arm 32 is to enable said curved device to act as a guide-shoe, the construction being such that said shoe presses at each of its ends and also at intermediate points upon the paper, whereby the latter is kept under control. The shoes or fingers 27, which overlie the paper at its side margins, are arranged between or at the inner sides of the lateral supports 32, the projections 31, upon which said shoes are mounted, extending inwardly or toward each other. Said supports are preferably parallel with the fingers 27 and stand outside the edges of the paper and above the surface of the platen.

What I claim as new, and desire to secure by Letters Patent, is—

1. In a front-strike type-writing machine, the combination with a series of types, a cylindrical platen, and means for guiding and feeding the paper from its entrance into the machine toward the printing-point, of a pair of pressure devices constructed and arranged wholly independently of said guiding and feeding means, for receiving the paper from said guiding and feeding means and conducting it away from the printing-point, said conducting devices being each provided with a supporting-arm arranged at the delivery side of the platen, said supporting-arms being so mounted at their extended ends upon a bar arranged longitudinally of the platen that they may be adjusted along said bar, wholly independently of said devices for guiding and feeding the paper toward the printing-point, and said bar being so arranged that the paper, as it is conducted away from the printing-point, does not pass between the bar and the platen. 105

2. In a front-strike type-writing machine, the combination with a series of types, a cylindrical platen, and suitable devices for guiding and feeding the paper toward the printing-point, the construction and arrangement being such that the paper is inserted in the machine in rear of the platen, of an independent device for guiding the paper upwardly from the printing-point, said device being constructed at one end to receive the paper from said guiding and feeding devices and at the other end to positively deflect the paper rearwardly over the point at which it is inserted in the machine, said guiding device being provided with a support which extends therefrom to a point wholly outside the field or area between the printing-point and the point of issuance of the paper, and which is so mounted at its extended end upon a bar arranged parallel with the platen that it may be adjusted along said platen without liability of interference from and wholly independently of said devices for guiding and feeding the paper toward the printing-point, and said bar being so arranged that the paper, as it feeds away from the printing-point, does not pass between the bar and the platen. 115

3. In a type-writing machine, the combination with a platen, of a device for guiding the

paper, and a bar upon which said device is supported and along which it may be adjusted and from which it extends forwardly directly over the platen, said guiding device including a finger which extends partly around the platen, and said bar being parallel with the platen and arranged relatively to the guide so that the paper feeds between said finger and the platen and passes onward over the bar in all adjusted positions of said guiding device.

4. In a type-writing machine, the combination with a platen of a fixed bar parallel therewith and arranged above the platen and in rear of a vertical line passing through the axis of the platen, and a device adjustably mounted upon said bar and extending forwardly therefrom directly over the platen for guiding the paper rearwardly over said bar after it has passed the printing-point.

5. In a type-writing machine, the combination with a platen, mechanism for feeding the paper toward the printing-point, a relatively-fixed bar parallel with the platen and arranged above the platen so that paper may be inserted in the machine in rear of said bar, and a spring-pressed device independent of said paper-feeding means and adjustably mounted upon said bar and extending forwardly therefrom directly over the platen, for guiding the paper rearwardly over said bar after it has passed the printing-point.

6. In a front-strike type-writing machine, the combination with a platen of a paper-guide curved to conform substantially to the curvature of the platen and terminating at its lower end in front of the platen and extending upwardly and rearwardly over the platen, a bar parallel with the platen and arranged in rear of the rear end of said guide, and means extending rearwardly over the platen for supporting said guide adjustably upon said bar, said supporting means being so arranged that the paper will pass under the guide and over the bar.

7. In a front-strike type-writing machine, the combination with a platen, of a paper-guide finger curved to conform substantially to the curvature of the platen and extending rearwardly over the platen, a bar parallel with the platen and arranged at the rear end of said guide-finger but not directly engaged thereby, and means extending directly over the platen forwardly from said bar for supporting said guiding-finger upon said bar and pressing said finger against the platen, said supporting and pressing means being so arranged that the paper will pass under said guiding-finger, and the rear end of the guiding-finger being bent away from the platen, so as to direct the paper over said bar.

8. In a type-writing machine, the combination with a cylindrical platen and a series of type-bars constructed to make impressions upon the paper in view of the operator, of means for feeding the paper toward the print-

ing-point, including a plate extending longitudinally of and parallel with the platen and contiguous thereto, so that the paper passes between said plate and the platen when moving to the printing-point, a device extending from and mounted independently of said plate to guide the paper rearwardly from the printing-point, and an arm supporting said guiding device and extending to a point wholly outside of the field or area between the printing-point and the point of issuance of the paper, and adjustably mounted at its extended end upon a longitudinally-arranged bar, so that said finger may be moved along said plate and platen, said bar being so arranged that the paper as it feeds away from the printing-point, does not pass between the bar and the platen.

9. In a front-strike type-writing machine, the combination with a series of type-bars and a cylindrical platen, of means for feeding the paper toward the printing-point, including a plate extending longitudinally of and parallel with the platen and contiguous thereto and supported below the printing-point, so that the paper passes between said plate and the platen, a paper-guide terminating at its lower end at said plate and also overlapping said plate but mounted independently thereof and terminating at its upper end above the platen, and a support for said paper-guide extending to a point wholly outside of the field or area between the printing-point and the point of issuance of the paper and adjustably mounted at its extended end upon a bar parallel with the platen, so that said finger may be moved along said plate and platen, and so arranged that the paper as it feeds away from the printing-point, does not pass between the bar and the platen.

10. In a type-writing machine, the combination of a platen, a pair of arms on the delivery side of the printing-point adjustable longitudinally of the platen according to the width of the paper used and so as to stand outside the edges of the paper, paper-guiding fingers connected to the arms and arranged on the inner sides thereof so as to overlie the paper at its side margins, and means for feeding the paper past the printing-point, under said guiding-fingers and between said arms.

11. In a type-writing machine, the combination of a platen, devices for passing the paper under the platen, a bar arranged lengthwise of the platen, a pair of arms adjustable along said bar and extending from said bar in a direction opposite that of the advance movement of the paper, and offset guiding-fingers carried by said arms; the organization being such that the paper is fed between said arms and under the guiding-fingers and over the bar.

12. In a front-strike type-writing machine, the combination with a cylindrical platen, of means for carrying the paper forwardly around the under side of the platen, and a pair of fingers which engage the side margins

of the paper to direct the latter rearwardly over the platen, said fingers being mounted upon supports which overhang the platen and are adjustably mounted upon a bar which extends longitudinally of the platen, and the relationship of the fingers, their supports and the bar being such that the paper advances over the bar, so that all of the writing remains exposed to view.

10 13. In a type-writing machine, the combination with a cylindrical platen and a platen-frame, of a pair of devices overhanging the platen and carried by said platen-frame, and means arranged between said devices and carried thereby for deflecting the paper rearwardly over the platen and between said devices.

15 14. In a front-strike type-writing machine, the combination with a cylindrical platen and a series of type-bars of devices for pressing the paper against the platen so as to cause it to feed toward the printing-point, and a pair of paper-guides curved substantially in conformity with the platen and constructed to direct the paper upwardly and rearwardly from the printing-point, said guides being provided with and arranged between spring-pressed vibratory lateral supports, and said lateral supports being arranged out of the path of the paper, and adjustably mounted upon a bar parallel with the platen, the construction and arrangement being such that the paper passes out between said supports.

20 15. In a front-strike type-writing machine, the combination with a cylindrical platen and suitable paper-feeding devices so constructed and arranged that the paper may be inserted in the machine in rear of the platen, of a guide for directing the paper upwardly from the printing-point and for positively deflecting the paper rearwardly over the point at which it is inserted in the machine, said guide being provided with a lateral support extending rearwardly over the platen and arranged out of the path of the paper, and said lateral support being adjustably mounted at its rear end upon a device over which the paper passes in issuing from the machine.

25 16. In a front-strike type-writing machine, the combination with a cylindrical platen of a pair of curved paper-guides each provided with a vibratory spring-pressed lateral support extending rearwardly over the platen, said lateral supports being arranged out of the path of the paper, and a bar upon which said lateral supports are adjustable, said bar being arranged above and parallel with the platen so that the paper may be inserted in the machine in rear of said bar, and said guides being disposed between said lateral supports, and the construction and arrangement being such that the paper may feed between said guides and the platen and pass out over said bar.

30 17. In a front-strike type-writing machine, the combination with a cylindrical platen of a flexible guide extending partly around the

platen and constructed to press the paper against the platen and direct it upwardly and backwardly, a laterally-arranged support to which said guide is attached at a point between the ends of the guide, said lateral support being arranged out of the path of the paper, and a bar upon which said lateral support is adjustable, the construction and arrangement being such that the paper feeds between said guide and the platen and passes onward over said bar.

35 18. In a type-writing machine, the combination with a platen of a pair of paper-guides and a bar along which said guides may be independently adjusted toward and from each other, said guides extending directly forward above the platen from said bar and the bar being arranged relatively to said guides so that the paper feeds between the guides and the platen and passes onward over the bar.

40 19. In a front-strike type-writing machine, the combination with any suitable mechanism for feeding the paper toward the printing-point, of a pair of devices for guiding the paper from the printing-point, and a bar parallel with the platen upon which both of said guiding devices are mounted so that they may vibrate independently and also so that they may be independently adjusted toward and from each other, the bar being arranged relatively to the guides so that the paper feeds between the guides and the platen and passes onward over the bar.

45 20. In a front-strike type-writing machine, the combination with a platen, of means, including a pair of paper-guides, each extending partly around the platen and each provided with a laterally-arranged support, and each of said lateral supports being adjustable along the platen and arranged out of the path of the paper, so that the latter may pass out between said supports, for feeding and guiding wide or narrow sheets around the platen in such manner as to leave all of the written portion of the page in full view of the operator.

50 21. In a front-strike type-writing machine, the combination with a cylindrical platen and a series of type-bars, of a roller constructed to press the paper against the platen so as to cause it to feed toward the printing-point, and a pair of paper-guides terminating at their forward ends in front of the platen and extending rearwardly over the platen and each curved substantially in conformity with the platen and constructed to direct the paper upwardly and rearwardly from the printing-point and each guide being provided with a spring-pressed lateral support, said lateral supports being arranged out of the path of the paper and mounted for adjustment along said platen independently of each other and of said roller, and the construction and arrangement being such that the paper passes between said lateral supports when issuing from the machine.

55 22. In a front-strike type-writing machine,

the combination with a cylindrical platen of a scale-plate supported below the printing-point, so that the paper passes between said plate and the platen, a pair of paper-guides whose lower ends overlap said plate and whose upper ends terminate above the platen, a laterally-arranged support for each of said paper-guides, and a bar upon which said lateral supports are independently adjustable, said bar being arranged parallel with the platen, and the construction and arrangement being such that the paper feeds between said guides and the platen and passes onward over said bar and between said lateral supports.

23. In a type-writing machine, the combination of a platen, a pressure-arm arranged at the delivery side of the platen, a paper-guide curved to match the platen and pivotally supported between its ends upon said arm, and a bar along which said arm is adjustable, the relationship of the platen, arm, guide and bar being such that after leaving the printing-point the paper does not pass between the bar and the platen.

24. In a type-writing machine, the combination with a paper-guide having ears, of an arm arranged laterally of said guide and provided with a lateral pin upon which said ears are pivoted, and a rod parallel with the platen along which said arm is adjustable, the relationship of the said parts being such that the paper when issuing from the machine passes over said rod and by said arm.

25. In a type-writing machine, the combination with a cylindrical platen, of a paper-guide provided with a lateral extension, an ear formed upon the paper-guide in line with the first ear, an arm arranged laterally of the paper-guide and provided with a lateral pin upon which said ears are pivoted, and a bar parallel with the platen and along which said arm is adjustable, the relation of the said parts being such that the paper when issuing from the machine passes over said rod and by said arm.

26. In a type-writing machine, the combination with a platen, of a bar parallel therewith, an arm adjustable along said bar and extending forwardly therefrom directly over the platen, a single lateral projection provided upon said arm, and a paper-guide supported wholly upon said single lateral projection, the relationship of the said parts being such that the paper after leaving the printing-point passes over said bar and by said arm.

27. In a type-writing machine, the combination with a platen, of a bar parallel therewith, a vibratory arm adjustable along said bar, and a paper-guide supported laterally upon the free end of said vibratory arm, the relation of the parts being such that the paper when issuing from the machine passes over said bar and by said arm.

28. In a type-writing machine, the combination with a platen, of a paper-guide pro-

vided with a spring-pressed lateral support, and a bar along which said support is adjustable, the relation of the said parts being such that the paper when issuing from the machine passes over said bar and by said lateral support.

29. In a type-writing machine, the combination with a platen, of a bar parallel therewith, a pair of paper-guides, arms upon which said guides are carried, said arms being pivotally mounted and independently adjustable along said bar, and said arms being also arranged laterally of said guides, and means for causing said arms to press said guides against the platen, the construction and arrangement being such that the paper feeds between said guides and the platen and passes onward over said bar and between said arms.

30. In a type-writing machine, the combination with a platen, of a bar parallel therewith, a pivoted arm adjustable along said bar, a paper-guide pivoted between its ends to said arm, and a spring, the relation of said parts being such that the paper after leaving the printing-point passes over said bar and by said arm.

31. In a front-strike type-writing machine, the combination with a platen of a bar arranged in rear of the printing-point, an arm adjustable along said bar and extending directly over the platen forwardly from said bar and arranged out of the path of the paper, a paper-guide arranged laterally of said arm and pivoted between its ends to said arm, and a spring for causing said arm to press the paper-guide against the platen.

32. In a type-writing machine, the combination with a platen of a longitudinally-grooved cylindrical rod parallel therewith, an arm pivotally engaging said rod and slidably therealong, a paper-guiding device carried by said arm, and a spring, one end of which is connected to said groove and the other end of which is arranged to put a tension upon said arm so as to cause the latter to press said guiding device against the platen.

33. In a type-writing machine, the combination with a platen of a longitudinally-grooved cylindrical rod parallel with said platen, a sleeve splined to the groove, a spring connected at one end to the sleeve, an arm to which the other end of said spring is connected, said arm being pivotally mounted upon said rod and constructed for adjustment therewith together with said sleeve, and a paper-guide carried by the free end of said arm.

34. In a type-writing machine, the combination with a platen of a longitudinally-grooved cylindrical rod parallel with said platen, a sleeve splined to the groove, a spring connected at one end to the sleeve, an arm to which the other end of said spring is connected, said arm being pivotally mounted upon said rod and constructed for adjustment therewith together with said sleeve, a

paper-guide carried by the free end of said arm, and means for adjusting the tension of said spring.

35. In a type-writing machine, the combination with a platen of a cylindrical rod parallel therewith, a sleeve splined to said rod and provided with a crown-ratchet, a spring surrounding said sleeve, a second crown-ratchet to which one end of said spring is attached, an arm carried by said rod and connected to the other end of said spring, said arm, sleeve, spring and crown-ratchets being simultaneously adjustable along said rod, and a paper-guide carried by the free end of said arm.

36. In a type-writing machine, the combination with a platen of a grooved cylindrical rod parallel therewith, a sleeve splined to said rod, a crown-ratchet surrounding said sleeve and fixed thereto, a second crown-ratchet loosely carried by said sleeve and engaging the first crown-ratchet, a spring arranged around said sleeve and attached to the second crown-ratchet, an arm upon said rod, said arm, sleeve, ratchets and springs being simultaneously adjustable along said rod, and a paper-guiding device carried by said arm.

37. In a type-writing machine, the combination with a cylindrical platen of a pair of paper-guides each provided with a lateral support arranged out of the path of the paper, a rod parallel with the platen and upon which said supports are independently adjustable, the construction and arrangement being such that the paper feeds between said guides and passes onward over said rod and between said lateral supports, and means for pressing said guides independently against the platen.

38. In a type-writing machine, the combination of a platen, a rod parallel therewith, a pair of paper-guides adjustable along said rod, and spring mechanism for pressing said guides against the platen, said spring mechanism including means for adjusting the pressure of both of said guides simultaneously.

39. In a type-writing machine, the combination with a platen of a rod parallel therewith, a pair of paper-guides carried by said rod and independently adjustable therealong, an independent spring for each paper-guide, and means for simultaneously adjusting said springs.

40. In a type-writing machine, the combination with a platen of a rod parallel therewith, a pair of paper-guides adjustable along said rod, an independent spring for each paper-guide, means for adjusting each of said springs independently, and means for adjusting both of said springs simultaneously.

41. In a type-writing machine, the combination with a platen-frame of a platen, a rod journaled in said platen-frame, a paper-guide adjustable along said rod, spring mechanism splined to said rod and connected to said paper-guide, and means for adjusting said rod

in its bearings to increase or diminish the tension of said spring mechanism.

42. In a type-writing machine, the combination with a platen and a platen-frame, of a paper-guide, a rod parallel with the platen upon which said guide is adjustable, spring mechanism connected to said guide and splined to said rod, bearings in the platen-frame in which said rod is journaled, a crown-ratchet carried by said platen-frame, a second crown-ratchet carried by said rod, and a spring for moving said rod endwise in its bearings in a direction to cause engagement of said crown-ratchets.

43. In a type-writing machine, the combination with a platen and a rod parallel therewith, of an arm bent at one end into a yoke which pivotally engages said rod, and carrying at the other end a laterally-arranged paper-guide.

44. In a type-writing machine, the combination with a platen and a rod parallel therewith, of an arm bent at one end into a yoke which pivotally engages said rod and carrying at the other end a laterally-arranged paper-guide, said yoke and said paper-guide being arranged upon the same side of the arm.

45. In a type-writing machine, the combination with a platen and a longitudinally-grooved rod parallel therewith, of an arm carrying at one end a paper-guide and bent at the other end to form a yoke which pivotally engages said rod, and a spring confined in said yoke and surrounding said rod, one end of the spring being suitably connected to said groove and the other end of the spring bearing upon said yoke.

46. In a type-writing machine, the combination with a platen and a grooved rod parallel therewith, of an arm carrying at one end a paper-guide and bent at the other end to form a yoke which pivotally engages said rod, a sleeve splined upon said rod and confined by said yoke, and a spring coiled around said sleeve, one end of the spring engaging said yoke and the other end of the spring being connected to said sleeve.

47. In a type-writing machine, the combination with a platen and a grooved rod parallel therewith, of an arm carrying at one end a paper-guide and bent at the other end to form a yoke which pivotally engages said rod, a sleeve splined upon said rod and confined by said yoke, a spring wound around said sleeve, one end of the spring engaging said yoke and the other end of the spring being connected to said sleeve, and means for adjusting the tension of the spring.

48. In a type-writing machine, the combination with the platen of a paper-guide adjustable along said platen, and a paper-gage which is set automatically in accordance with the position to which said paper-guide is adjusted.

49. In a type-writing machine, the combination with a platen of a roller for feeding the

paper toward the printing-point, a device for guiding the paper away from the printing-point, said guiding device being adjustable longitudinally of the platen and independently of said feeding-roller, and a paper-gage attached to said guiding device.

50. In a type-writing machine, the combination with a platen of a platen-scale, a paper-guide extending from said scale partly around 10 the platen, and a paper-gage secured to said paper-guide.

51. In a type-writing machine, the combination with a platen and a platen-scale, of a paper-gage mounted for adjustment longitudinally of the platen and having a part which extends to said platen-scale, so that the adjustment of said paper-gage may be determined by reference to said platen-scale. 15

52. In a front-strike type-writing machine, 20 the combination with a platen of a rod arranged over the platen and parallel therewith, a forwardly-extending paper-guide mounted adjustably upon said rod, and a rearwardly-extending paper-gage secured 25 to said forwardly-extending device so as to move therewith along said rod.

53. In a front-strike type-writing machine, 30 the combination with a platen of a rod arranged thereover and parallel therewith, a forwardly-extending arm adjustably mounted upon said rod and arranged out of the path 35 of the paper, a laterally-disposed paper-guide carried by the forward end of said arm, and a rearwardly-extending paper-gage attached to said arm, the construction and arrangement being such that paper enters between 40 said guide and the platen and passes onward over said rod.

54. In a front-strike type-writing machine, 45 the combination with a platen of a rod arranged thereover and parallel therewith, a forwardly-extending arm adjustably mounted upon said rod and arranged out of the path of the paper, a laterally-disposed paper-guide carried by the forward end of said arm, and a rearwardly-extending paper-gage attached 50 to said arm, said paper-gage being offset or out of line with said arm.

55. In a front-strike type-writing machine, 55 the combination with a platen of a paper-shelf, a rod arranged over the platen, an arm adjustably mounted upon said rod, a lateral paper-guide carried by said arm, and an extension upon said arm reaching rearwardly to said paper-shelf.

56. In a type-writing machine, the combination with a platen of a rod arranged thereover and parallel therewith, an arm carrying 60 at its forward end a lateral paper-guide and its rear end bent to form a yoke which pivotally engages said rod, said arm also having

a rearwardly-extending portion which forms a paper-gage.

57. In a type-writing machine, the combination with a paper-shelf, a platen, and a rod 65 arranged over the platen and parallel therewith, of a paper-gage adjustable upon said rod and extending rearwardly therefrom to a point in rear of the working face of said paper-shelf. 70

58. In a type-writing machine, the combination of a paper-shelf having a longitudinal depression, a platen, a rod over said platen, and a paper-gage adjustable upon said rod and extending rearwardly into said depression. 75

59. In a type-writing machine, the combination with a paper-shelf and a platen, of a rod arranged over said platen, a forwardly-extending arm carrying a paper-guide, and a paper-gage attached to said arm and extending rearwardly to a point beyond the working face of said paper-shelf. 80

60. In a front-strike type-writing machine, the combination with a platen of a bar parallel therewith and arranged so as not to intercept the view of any of the written portion of the paper, a spring-pressed arm adjustably mounted upon said bar, a paper-guide carried upon the free end of said arm, and an independently spring-pressed roller also carried upon the free end of said arm. 85

61. In a type-writing machine, the combination with a platen of a bar parallel therewith, an arm adjustably mounted upon said bar, a lateral pin provided upon said arm, a paper-guide pivoted upon said lateral pin, an independent frame also pivoted upon said pin and carrying a roller, and a spring for pressing said roller independently against the 90 platen, the construction and arrangement being such that the paper enters or feeds between said guide and said roller and the platen and passes onward over said bar. 100

62. In a type-writing machine, the combination of a platen, a bar arranged parallel therewith, an arm supported at one end upon said bar and extending partly around the platen and above the surface thereof, and a lateral guiding-finger carried by said arm and pressing upon the platen, the relationship of said parts being such that the paper as it leaves the printing-point passes under said finger and over said bar and by said arm. 105

Signed at the borough of Manhattan, city 110 of New York, in the county of New York and State of New York, this 3d day of April, A. D. 1900.
